R. C. RUSSELL

LOOSE LEAF BOOK

Filed July 28, 1925

UNITED STATES PATENT OFFICE.

ROBERT C. RUSSELL, OF PITTSBURGH, PENNSYLVANIA.

LOOSE-LEAF BOOK.

Application filed July 28, 1925. Serial No. 46,606.

To all whom it may concern:

Be it known that I, ROBERT C. RUSSELL, a citizen of the United States, and resident of Pittsburgh, in the county of Allegheny and State of Pennsylvania, have invented certain new and useful Improvements in Loose-Leaf Books; and I do hereby declare the following to be a full, clear, and exact description of the invention, such as will enable others skilled in the art to which it appertains to make and use the same.

This invention relates to improvements in loose leaf books and more particularly to that type in which the cross links which pass through the leaves of the book are connected with the covers of the book through the medium of longitudinally movable devices which cooperate with the leaf-penetrating links to lock them normally in position,—the object of my present invention being to provide simple and efficient key-controlled means for locking the locking bars against longitudinal withdrawing movement and causing them to be automatically locked when moved inwardly to lock the cross links.

With this and other objects in view, the invention consists in certain novel features of construction and combinations of parts as hereinafter set forth and pointed out in the claims.

In the accompanying drawings;

Figure 1 is a face view partly in section and partly broken away showing back and cover members of a book and illustrating an embodiment of my invention;

Figure 2 is an enlarged view in transverse section;

Figure 3 is a view of the key, and

Figure 4 is a view illustrating the locking bars.

The cover members of a book are indicated at 1, 1, and the back member at 2. To each cover member, a plate 3 is secured, and each plate is bent upon itself in a manner to provide guides 4, portions of which overlie respective edge portions of the back member 2. Each guide 4 receives locking bars 5 and 6, each of which may be provided at one end with a thumb or finger piece 7 and these locking bars are preferably made flat or rectangular in cross section. Each locking bar is recessed as at 8 and formed with pins or fingers 9 disposed longitudinally of the bar and projecting over a portion of the recesses so as to leave openings 9^a. The guides 4 are provided at intervals with notches 10 to receive the perforated end portions of links or cross bars 11 which are adapted to pass through suitable perforations 12 in the leaves 13,—the perforations in said links or cross bars 11 being caused to enter the openings 9^a of the locking bars and receive the pins or fingers 9 on said bars when the latter are moved inwardly toward each other, thus connecting said bars or links with the book covers through the medium of the locking bars and guides.

In the embodiment of the invention shown in the drawings, two locking bars are provided in a guide at each edge portion of the back 2 and the inner edge portions of the cover members 1, but if desired, locking bars may be provided at one side only of the back and the links or cross bars 11 hinged to the opposite cover member in any suitable manner.

The locking bars 5—6 are provided at 80 their inner ends with extensions 14 having engaging means, (such as teeth 15 for example,) to cooperate with engaging means, (such as teeth 16 for example) at or near the ends of a locking link or member 17 85 located within the guide 4, to lock the locking bars against withdrawing endwise movement. The locking link is maintained normally in locked relation to the locking bars, by means of a spring 18 which is secured 90 intermediate of its ends to said link and having its end portions bearing against the inner wall of the guide 4. In order to provide means to prevent displacement of the locking link 17 and spring within the guide 4, pins 19 are passed transversely through the guide between the spring and link, but are so disposed as not to interfere with sufficient movement of the link to release the locking bars.

A key hole 20 is so located in each guide 4 that when a key 21 is made to enter the same, its inner end will become disposed behind the locking link. When the key thus inserted is turned, the locking link or member 17 will be moved away from the engaging members of the locking bars and the latter will thus be released so that they may be moved endwise to release the cross links 11. It is apparent that when the lock-

ing bars are moved toward each other, they will become automatically locked to the locking link.

In order to prevent the locking bars from being fully withdrawn from the guides 4, pins 22 are passed transversely through the guides and the locking bars are notched or recessed as at 23 to provide shoulders 24 to engage said pins. The shoulders 25 at the other ends of the recess 23 will, in cooperation with the pins 22, limit inward movement of the locking bars.

Having fully described my invention what I claim as new and desire to secure by Letters-Patent, is:—

1. In a loose leaf book, the combination with guide means, and cross links, of a plurality of locking bars movable in the same guide means and provided with means to engage said cross links, locking means within the guide means to engage the inner end portions of adjacent locking bars in the same guide means and lock the said bars from endwise withdrawing or releas-

ing movement, and means to disengage said locking means from the plurality of locking bars.

2. In a loose leaf book, the combination with guide means, and cross links, of two locking bars in the same guide means provided with means to engage said cross links, each of said locking bars having an engaging member at its inner end, a locking member within the guide means and having engaging means cooperable with the engaging means of the two locking bars to lock the latter against longitudinal withdrawing or releasing movement, a spring normally pressing said locking member into locking relation to both locking bars, means to prevent displacement of said locking member and spring, and means to retract the locking member from locking relation to the locking bars.

In testimony whereof, I have signed this specification.

ROBERT C. RUSSELL.
